UNITED STATES PATENT OFFICE.

ELLSWORTH A. HAWTHORNE, OF BRIDGEPORT, CONNECTICUT.

LAMP.

1,099,087.

Specification of Letters Patent.

Patented June 2, 1914.

Application filed August 2, 1913. Serial No. 782,569.

To all whom it may concern:

Be it known that I, ELLSWORTH A. HAWTHORNE, a citizen of the United States, and a resident of Bridgeport, county of Fairfield, and State of Connecticut, have invented an Improvement in Lamps, of which the following description, in connection with the accompanying drawings, is a specification, like characters on the drawings representing like parts.

This invention relates to lamps, and more especially to electric lamps for use on vehicles, such for example as motor cycles, and will be best understood by reference to the following specification, when taken in connection with the accompanying drawings of one specific embodiment thereof, while its scope will be more particularly pointed out in the appended claims.

20 In the drawings: Figure 1 is a side elevation of a lamp embodying my invention; and Fig. 2 is a plan view of the same, partly in section.

Referring to the drawings, and to the embodiment of my invention which I have selected for illustration, I have there shown a lamp comprising a lamp casing 3, provided at its front with a light-transmitting element 4 of any appropriate character to 25 transmit the light from a suitable light-producing element 5, herein in the form of an electric incandescent bulb. The casing 3 may be supported in any other appropriate manner, but herein a support 6, of generally 30 U-shaped form, is provided with two arms 7 and 8, the latter being secured to the back of the lamp casing by any appropriate means, as for example a plurality of rivets 35 9, extending through the arm and back wall 40 of the casing. The terminal portions of the arms 7 and 8 may be appropriately formed for attachment to any suitable bracket (not shown).

The bulb 5 may be otherwise appropriately mounted, but herein is provided with a usual shell or neck 10, having secured thereto a pin 11, located in a bayonet slot 12 provided in a tubular connection 13 leading to the lamp, and extending rearwardly 45 from the casing. Adjacent the lamp casing, the connection 13 extends through an aperture 14 in the arm 8, and adjacent its rear end, it extends through an aperture 15 in the arm 7.

50 The tubular connection 13 may serve as a housing for any usual or desired conductors

leading to the lamp terminals (not shown), and the rear end of the connection in such case preferably serves for the attachment of a plug 16 at the terminal portion of a current supply cable 17. The plug 16 may be secured to the connection 13 in any other appropriate manner, but herein is provided with a pin 18 located in a bayonet slot 19 formed in the connection. The attachment 55 of the plug and lamp to the connection is such that either may be removed from its place, yet without removing the connection from its support and without disconnecting the lamp casing from its support.

While I have herein shown and described one form or embodiment of my invention for illustrative purposes, and have disclosed and discussed in detail the construction and arrangement incidental to one specific application thereof, it is to be understood that the invention is limited neither to the mere details or relative arrangement of parts, nor to specific embodiment herein shown, but that extensive deviations from the illustrated form or embodiment of the invention may be made, without departing from the principles thereof.

Having thus described my invention, what I claim and desire to procure by Letters Patent is:—

1. In a lighting apparatus, the combination of a lamp casing, a lamp within said casing, a tubular connection leading to said lamp and extending rearwardly from said casing, a current-conducting cable having an attaching plug extending within and having a readily detachable attachment to the rear end of said connection, and a support through which said connection extends, the attachment of the cable being independent 90 of the attachment for said connection afforded by said support.

2. In a lighting apparatus, the combination of a lamp casing, a lamp within said casing, a tubular connection leading to said lamp and extending rearwardly from said casing, and supporting means for said connection having an aperture to receive said connection adjacent its rear end and another aperture to receive said connection adjacent said casing.

3. In a lighting apparatus, the combination of a lamp casing, a lamp within said casing, a tubular connection leading to said lamp and extending rearwardly from said casing, and a support through which said

connection extends at two points one of which is adjacent said casing and the other adjacent the rear end of said connection.

4. In a lighting apparatus, the combination of a lamp casing, a lamp within said casing, a tubular connection leading to said lamp and extending rearwardly from said casing, and a substantially U-shaped support having two arms each provided with

an aperture through which said connection 10 extends.

In testimony whereof, I have signed my name to this specification, in the presence of two subscribing witnesses.

ELLSWORTH A. HAWTHORNE.
